ROTARY TAKE-UP FOR SEWING MACHINES

Filed June 15, 1948

4 Sheets-Sheet 1

This technical drawing illustrates a vacuum chamber assembly, likely for a scientific or industrial application. The drawing shows a large, curved vacuum vessel (14) with a flange (10) on the right side. A central vertical tube (29) extends from the flange, featuring a valve assembly with components labeled A, N, and P. A horizontal tube (11) is connected to the main vessel and has a valve (20) on its side. The interior of the vessel is shown with various components labeled with numbers: 15, 16, 17, 18, 19, 21, 22, 23, 24, 25, 26, 27, 28, 29, 30, 31, 32, 33, 34, 35, 36, and 37. A small circular component labeled 'S' is also visible. The drawing uses solid lines for major components and dashed lines for internal structures and smaller parts.

ROTARY TAKE-UP FOR SEWING MACHINES

Glen A. Holland, Bronxville, N. Y., assignor to
The Yale & Towne Manufacturing Company,
Stamford, Conn., a corporation of Connecticut

Application June 15, 1948, Serial No. 33,136

31 Claims. (Cl. 112—248)

1

This invention relates to a sewing machine and more particularly, a sewing machine of the type shown and described in my application Ser. No. 630,288, filed November 23, 1945.

As is set forth in my earlier application, there has long been sought a domestic sewing machine that can be threaded by a simple manipulation of the thread, and without the rather complex and intricate manipulation of the thread that is necessary in present day domestic sewing machines. The art has also long sought a domestic sewing machine having a simple rotary take-up mechanism.

While today there are numerous patents showing rotary take-up mechanisms, these rotary take-ups do not lend themselves to the type of simple threading that I believe is essential in a domestic sewing machine. In addition, the rotary take-ups of the prior art have a tendency to entrap the thread when the thread is broken so as to wind considerable lengths of the thread about the mechanism. This makes it necessary to perform a difficult thread unwinding and disentangling operation each time that the thread is broken. In order to minimize the damage done, thread cutters are provided in commercial sewing machines of the particular class, the thread cutters serving to cut the thread and thereby to prevent the entrapping thereof. However, thread cutters are not entirely satisfactory, and certainly are not desirable in sewing machines.

In my application supra, I disclose a rotary take-up mechanism that is particularly adapted for ready cooperation with a thread placed across its path of movement. Thereby, my take-up mechanism is readily adaptable for use in a machine of the type in which the thread is moved preferably in a single plane from the spool to the needle and without any manipulation relatively to auxiliary guide means such as is required generally in prior art machines. In addition, the take-up mechanism of my earlier application is self-stripping, so that its mere movement with the thread during the take-up stroke is effective to move the thread into a position wherein it strips off the take-up mechanism.

To accomplish the purposes of the invention, the machine of my earlier application utilizes a rotary take-up finger that contacts the thread at a particular point of its movement where the thread is maintained across the path of the take-up finger. The take-up finger strikes the thread and then rotates to take up the thread. During the take-up rotation, a camming or stripping surface of the take-up finger moves into con-

2

tact with the thread and gradually cams the thread relatively to the take-up finger into position for full stripping from the finger. While this mechanism of my earlier application is extremely effective, I believe that I have now conceived a rather considerable improvement thereon whereby far better results are obtained than are possible in my earlier machine.

Thus, in my new machine, I utilize a take-up finger that moves at a variable speed and with the speed variations so arranged that after the take-up stroke is completed, the finger moves faster than the movement of the thread by the usual bobbin hook. Because of the particular arrangement, slack is developed between the take-up finger and the thread. During that portion of the cycle when the slack is so developed, the take-up finger is so positioned relatively to the thread that there are no retaining or detent means present to hold the thread against endwise movement off the finger. As a matter of fact, the finger is preferably so constructed that at the particular moment when the slack is developed, the thread will move with considerable ease off the end of the finger. Because of the particular arrangement, the thread sheds very readily off the take-up finger during the creation of the slack between the thread and the finger, and immediately thereafter the bobbin hook takes up all the slack of the thread and positions the thread across the path of the take-up finger just as the said finger once again contacts the thread for beginning the next take-up cycle.

While I prefer that arrangement of my structure whereby slack is actually created between the finger and the thread, it is possible to operate my sewing machine effectively without slack, by forming the surface of the take-up finger so that it readily sheds the thread just after the end of the take-up stroke. However, it is well at this point to emphasize that the most effective results are obtained through the utilization of the entire combination of my invention rather than through utilization of sub-combinations thereof. Nevertheless, I believe that I am entitled to claims covering sub-combinations of my invention, and such claims will be appended hereto.

I have thus outlined rather broadly the more important features of my invention in order that the detailed description thereof that follows may be better understood, and in order that my contribution to the art may be better appreciated. There are, of course, additional features of my invention that will be described hereinafter and which will form the subject of the claims ap-

bended hereto. Those skilled in the art will appreciate that the conception on which my disclosure is based may readily be utilized as a basis for the designing of other structures for carrying out the several purposes of my invention. It is important, therefore, that the claims to be granted me shall be of sufficient breadth to prevent the appropriation of my invention by those skilled in the art.

Referring now to the drawings, Fig. 1 is an elevation of my sewing machine illustrating its general construction and outer contour. Fig. 2 is a vertical view of the front end of my sewing machine with certain of the parts thereof removed so as to better illustrate the operating mechanism. Fig. 3 is a view looking downwardly on the mechanism of Fig. 2. Fig. 4 is a perspective view of the take-up finger and the parts immediately cooperating therewith. Fig. 4a is a view showing the take-up finger of Fig. 4 in a different position. Fig. 5 is a vertical section taken along lines 5-5 of Fig. 2. Fig. 6 is a vertical section taken along lines 6-6 of Fig. 5. Figs. 7 to 10 are diagrammatic views illustrating different operating positions of the take-up finger and thread.

Referring now more particularly to the drawings, and especially Fig. 1, my sewing machine comprises a hollow base member 10 that is formed integrally with an upper hollow arm 11, arm 11 having formed on its left end what I term a head 12. The base of the machine is so designed that a rubber pad 13 may be secured thereto for the purpose of holding the machine against slipping on a smooth surface, and also for dampening vibrations.

Within the base of the machine 10 there is mounted a suitable electric motor 14 that drives a conventional bobbin hook 15, the hook 15 being carried on the main shaft of the motor 14. The extreme right end of the motor shaft carries a pulley 16, the pulley 16 driving a belt 17 that in turn drives an upper shaft 18. A hand wheel 19 is secured to the shaft 18 for imparting rotation thereto when desired. In accordance with the teachings of the prior art, the shaft of the motor 14 and the bobbin hook 15 makes two rotations for every rotation imparted the upper shaft 18.

For covering the forward end of the head 12 and the upper forward portion of the arm 11, I utilize a cover member designated by the letter C and pivoted on a shaft 20 relatively to the arm 11. The cover C has a part 21 that is adapted to cover the forward end of the head 12 and to complete the general streamlined appearance of the machine, as is apparent from Fig. 1. At this point, it will be well to indicate that the general construction of the machine of my invention so far described is the same as that set forth in more detail in my earlier application to which reference may be made.

The forward end of the upper shaft 18 is suitably mounted in a bearing member 22 supported by parts of the head casting as well illustrated in Fig. 5. The shaft 18 has secured thereto for integral rotation therewith what I call a driving disc 23, this driving disc being rather oddly shaped in order that it may be properly counterbalanced. A driving pin 24 is carried by a portion of the driving disc 23 as is probably best seen in Fig. 6, and mounted about this driving pin is a relatively small crank 25 and a relatively larger and longer crank 26. The longer crank 26 is pivoted at 27 to a bracket 28 secured about the nee-

dle shaft 29 and there held by a screw 30. It is, of course, obvious that the lower part of the bracket 28 is bifurcated to fit about the needle shaft 29 and that the arms of the bifurcated bracket are held by the screw 30.

The relatively smaller crank 25 is pivoted at 31 to a crank 32, the crank 32 being formed as an integral part of a shaft 33. The axis of the shaft 33 is vertically above and somewhat to the right of the axis of shaft 18 as can best be seen from Figs. 2 and 5. In other words, there is an eccentric relationship between shafts 18 and 33 so that while shaft 33 will make one revolution during the time that the shaft 18 makes one revolution, the shaft 33 will operate at varying speeds during the revolution as against a uniform speed of the shaft 18.

Shaft 33 is suitably supported for rotation through a bearing disc 35 carrying a bearing member 36 as is best seen in Fig. 3. Secured for rotation integrally with the shaft 33 is a take-up disc 37 held assembled to the shaft 33 and its crank 32 by a screw 38. Take-up disc 37 has formed thereon a take-up finger 39 best shaped as is well illustrated in Figs. 4, 4a, and 5. It will be noted that the take-up finger has a detent portion 40 that in one position of the finger and disc overlies a part of the thread so as to prevent endwise removal of the thread from the finger. I shall presently describe in detail the operation of the finger and the manner in which it coacts with the thread.

The bobbin hook 15, as was earlier indicated, is of conventional construction and operates as do all such mechanisms. Cooperating with the hook is a feed system designated generally by reference letter F and best illustrated in Figs. 2 and 6. This feed system is adapted to feed the cloth in the usual manner well known in the art and for that reason I shall not describe its operation. My machine utilizes, of course, the usual needle N secured to the needle bar 29 and moving vertically therewith through operation of the crank 26 actuated by the upper rotating shaft 18. I think it will be unnecessary to describe further the operation of the needle, as its action is the same as that of prior art needles.

A presser foot assembly P is also utilized by me and is operated by a pivoted lever 41 as is usual in this art. It is the further function of the pivoted lever 41 to control the tension between a pair of take-up discs 42 best shown in Fig. 2, so that when the presser foot is in its position of Figs. 2 and 6, tension is applied between the discs 42. However, when the presser foot is elevated from its position of Fig. 6, tension is relieved between the discs 42. For adjusting the tension applied by discs 42 to the thread, I utilize an adjusting knob 43, the functioning of which is the same as that of a similar knob in my earlier application.

In my machine I also use an automatic threading attachment A, shown in the several figures, and relatively to which the presser foot moves vertically. Because this automatic threading attachment is not part of the invention herein claimed, I shall not describe its operation.

In my earlier application, certain thread guiding means are shown mounted on the cover C. In the present application, I show thread guiding means mounted not on the cover C, but on a special hinged plate that I have developed for the purpose. This hinged plate is designated by reference numeral 45 and is pivoted at 46 to a part of the casting of the head 12 as probably

best seen in Figs. 2, 4, and 5. Plate 45 is equipped with a pin 47 whereby it may be moved from the position of Figs. 2 and 5 to the open position of Fig. 4. A spring 48 functions to hold the plate 45 in the position of Fig. 2. Formed integrally with the plate 45 is an upper shelf 49 having a groove 50 cut therein. Hinged plate 45 has a lower shelf 51 also formed integrally therewith, and when the plate 45 is in the closed position of Figs. 2 and 5, the upper and lower shelves 49, 51 lie above and below a bent rod 52 extending between parts 53 and 54 of the head of the machine.

When it is desired to thread the machine, the thread T is advanced as is best illustrated in Fig. 5 from a spool supported in the machine at S in Fig. 1. The thread then runs between the two discs 42 of the tension mechanism and is dropped vertically across the diametric path of the take-up finger 39 and threaded into the needle N, as probably best seen in Figs. 2 and 5. The thread will lie outwardly of the bent rod 52 as is best seen in Figs. 4 and 5 and to the right of a guide pin 55 best shown in Figs. 2 and 4. Thereafter, when the hinged plate 45 is moved to its closed position of Figs. 2 and 3, the shelf 49 and its groove 50 will coat with the bent wire 52 as best seen in Fig. 3 to form a guide opening for the movement of the thread T. Thereafter, the thread will pass over the second shelf 51 and be held thereby close to the plate 56 from which extends the pin 55 whereby to best position the thread relatively to the needle N. It will now be readily understood that in threading my machine it is merely necessary to place the thread over the tension mechanism and then vertically down to the needle N. Thereby, I avoid the extremely tedious and difficult threading operation required by domestic machines now available to the public.

I shall now describe the action of my take-up finger 39, and for this purpose I refer particularly to Figs. 2, 4, 4a, and 7 to 10. In Fig. 2, the take-up finger 39 is shown just prior to its contact with the thread T, the take-up finger rotating counter-clockwise as indicated by the arrow 57. The bobbin hook 15 has just about completed its take-up stroke so that when the finger 39 strikes the thread T, the thread will be positioned substantially vertically between the take-up discs 42 and the needle N.

In Fig. 7 I show the take-up finger just after it has contacted the thread T and as the bobbin hook 15 is beginning to give up the thread T. It will be noted in Fig. 7 that the detent portion 40 of the take-up finger 39 overlies the thread T and prevents any endwise movement of the thread off the take-up finger. In Fig. 4, there is shown in perspective the relation of the take-up finger 39 and its detent portion 40 relatively to the thread T after the take-up finger has progressed further counter-clockwise from the position of Fig. 7.

In Fig. 8 we see once again the action of the take-up finger 39 and here again the detent portion 40 is in overlying relation to the thread T. In Fig. 9, the take-up finger still remains in overlying relationship to a part of the thread T, but there is about to begin in Fig. 9 an acceleration of the take-up finger so as to rapidly withdraw it from the thread T and thereby create a slack condition between it and the thread T. Incidentally, the take-up finger also accelerates upwardly from its position of Figs. 2 and 7 so as to effect a fast

take-up action as is desirable in this art and as will be understood by those skilled in the art.

Because of the crank operation and the eccentric relationship of the take-up disc 37 to the rotation of the drive shaft 18, the take-up finger will accelerate in its movement towards the position of Fig. 10 from the end of the take-up stroke as has already been indicated. Therefore, in Fig. 10 we find considerable slack in the thread T. Moreover, we find the detent portion 40 of the take-up finger 39 so positioned relatively to the slack thread T as to be ineffective to hold thread T against movement off the finger. Therefore, it may be said that when the take-up finger reaches its position of Fig. 10, due to its general shape and the slack between it and the thread, the thread is effectively shed. Because the thread is shed and because the bobbin hook 15 acts in Fig. 10 to begin a rapid take-up of the thread T, we find the thread T moving rapidly to the dotted line position shown at T' in Fig. 10. Moreover, when the thread is approximately in its dotted line position at T', the take-up finger has already progressed to its dotted line position at 39 shown in Fig. 10. The action of the bobbin hook 15 is now so swift that from the position of Fig. 10 the thread is rapidly moved toward the position of Fig. 2 where the take-up finger 39 is again ready to contact the thread and to begin a second take-up cycle.

It will be well to set forth at this point that the basic contribution of my invention may be achieved through other particular relationships of the several parts, but yet in accordance with my basic concept. Therefore, I intend to claim that basic concept and the basic structure whereby the concept is reduced to practice so as to prevent the appropriation of my invention by those skilled in the art through the utilization of structures varying from that I have herein contributed but still operating in accordance with my teachings.

I now claim:

1. In a sewing machine, a rotating take-up finger having a surface for contacting the thread as said finger rotates, said finger taking up the thread by rotation to a take-up position, and means for rotating said take-up finger faster than said thread is moved from its take-up position whereby said take-up finger sheds said thread as said take-up finger moves beyond its take-up position.

2. In a sewing machine, a rotating take-up finger having a surface for contacting the thread as said finger rotates, said finger taking up the thread by rotation to a take-up position, said take-up finger having a stripping surface moving into contact with the thread as said finger rotates from take-up position, and means for rotating said take-up finger faster than said thread is moved from its take-up position whereby said take-up finger sheds said thread as said take-up finger moves beyond its take-up position.

3. In a sewing machine, a rotating take-up finger having a surface for contacting the thread as said finger rotates, said finger taking up the thread by rotation to a take-up position, said take-up finger having a stripping surface moving into contact with the thread as said finger rotates from take-up position whereby said take-up finger sheds said thread as said take-up finger moves beyond its take-up position.

4. In a sewing machine, a take-up finger, means mounting said finger for rotation about a fixed axis and in a predetermined plane, said

take-up finger having a surface for contacting the thread as said finger rotates, said finger taking up the thread by rotation to a take-up position, and means for rotating said take-up finger faster than said thread is moved from its take-up position whereby said take-up finger sheds said thread as said take-up finger moves beyond its take-up position.

5. In a sewing machine, a take-up finger, means mounting said finger for rotation about a fixed axis and in a predetermined plane, said take-up finger having a surface for contacting the thread as said finger rotates from initial contact with said thread, said finger taking up the thread by rotation to a take-up position, said take-up finger having a stripping surface moving into contact with the thread as said finger rotates from take-up position, and means for rotating said take-up finger faster than said thread is moved from its take-up position whereby said take-up finger sheds said thread as said take-up finger moves beyond its take-up position.

6. In a sewing machine, a take-up finger, means mounting said finger for rotation about a fixed axis, said take-up finger having a surface for contacting the thread as said finger rotates from initial contact with said thread, said finger taking up the thread by rotation to a take-up position, and means for rotating said take-up finger faster than said thread is moved from its take-up position whereby to develop slack between said finger and said thread so that said take-up finger sheds said thread as said take-up finger moves beyond its take-up position.

7. In a sewing machine, a take-up finger, means mounting said finger for rotation about a fixed axis, a drive shaft rotatable in an axis parallel but offset relatively to the axis of rotation of said finger, a crank connection between said drive shaft and the take-up finger whereby said take-up finger rotates at a varying speed relatively to the speed of said drive shaft, said take-up finger having a surface for contacting the thread as said finger rotates, said finger taking up the thread by rotation to a take-up position, and said take-up finger having a stripping surface moving into contact with the thread as said finger rotates from take-up position.

8. In a sewing machine, a take-up finger, means mounting said finger for rotation about a fixed axis, a drive shaft rotatable in an axis parallel but offset relatively to the axis of rotation of said finger, a crank connection between said drive shaft and the take-up finger whereby said take-up finger rotates at a varying speed relatively to the speed of said drive shaft, said take-up finger having a surface for contacting the thread as said finger rotates from a position of initial contact with said thread, said finger taking up the thread by rotation to a take-up position, said take-up finger having a stripping surface moving into contact with the thread as said finger rotates beyond take-up position toward said position of initial contact, said crank connection rotating said take-up finger faster than said thread is moved from its take-up position whereby said take-up finger sheds said thread as said take-up finger moves beyond its take-up position.

9. In a sewing machine, a rotary take-up finger having a surface for contacting the thread, a rotary hook for taking up the thread in cooperative relation to said take-up finger, said finger taking up the thread by rotation from an initial

thread contacting position toward take-up position, said hook taking up the thread and moving it to position for initial contact by said take-up finger as the take-up finger rotates from said take-up position toward said initial contact with the thread, and means for rotating said take-up finger faster than said thread is moved immediately from its take-up position by said hook whereby said take-up finger develops slack between it and said thread as said take-up finger moves from its take-up position toward initial contact with said thread.

10. In a sewing machine, a rotary take-up finger having a surface for contacting the thread, a rotary hook for taking up the thread in cooperative relation to said take-up finger, said finger taking up the thread by rotation from an initial thread contacting position toward take-up position, said hook taking up the thread and moving it to position for initial contact by said take-up finger as the take-up finger rotates from said take-up position toward said initial contact with the thread, said take-up finger having a stripping surface in contact with the thread as said finger rotates from take-up position toward said initial contact with said thread, and means for rotating said take-up finger faster than said thread is moved immediately from its take-up position by said hook whereby said take-up finger develops slack between it and the thread as said take-up finger moves from its take-up position toward initial contact with said thread.

11. In a sewing machine, a rotary take-up finger having a surface for contacting the thread, a rotary hook for taking up the thread in cooperative relation to said take-up finger, said finger taking up the thread by rotation from an initial thread contacting position toward take-up position, said hook taking up the thread and moving it to position for initial contact by said take-up finger as the take-up finger rotates from said take-up position toward said initial contact with the thread, and said take-up finger having a stripping surface moving into contact with the thread as said finger rotates from take-up position and toward initial contact with said thread whereby said thread is stripped from said take-up finger.

12. In a sewing machine, a take-up finger, means mounting said finger for rotation about a fixed axis, a drive shaft rotatable in an axis parallel but offset relatively to the axis of rotation of said finger, a crank connection between said drive shaft and the take-up finger whereby said take-up finger rotates at a varying speed relatively to the speed of said drive shaft, said take-up finger having a surface for contacting the thread, a rotary hook for taking up the thread in cooperative relation to said take-up finger, and rotating in fixed relation to said drive shaft, said finger taking up the thread by rotation from an initial thread contacting position toward take-up position, said hook taking up the thread and moving it to position for initial contact by said take-up finger as the take-up finger rotates from said take-up position toward said initial contact with the thread.

13. In a sewing machine, a take-up finger, means mounting said finger for rotation about a fixed axis, a drive shaft rotatable in an axis parallel but offset relatively to the axis of rotation of said finger, a crank connection between said drive shaft and the take-up finger whereby said take-up finger rotates at a varying speed relatively to the speed of said drive shaft, said

take-up finger having a surface for contacting the thread, a rotary hook for taking up the thread in cooperative relation to said take-up finger, and rotating in fixed relation to said drive shaft, said finger taking up the thread by rotation from an initial thread contacting position toward take-up position, said crank rotating said take-up finger faster than said thread is moved immediately from its take-up position by said hook whereby said take-up finger sheds said thread as said take-up finger moves from its take-up position toward initial contact with said thread, and said hook taking up the thread and moving it to position for initial contact by said take-up finger as the take-up finger rotates from said take-up position toward said initial contact with the thread.

14. In a sewing machine, a take-up finger, means mounting said finger for rotation about a fixed axis, a drive shaft rotatable in an axis parallel but offset relatively to the axis of rotation of said finger, a crank connection between said drive shaft and the take-up finger whereby said take-up finger rotates at a varying speed relatively to the speed of said drive shaft, said take-up finger having a surface for contacting the thread, a rotary hook for taking up the thread in cooperative relation to said take-up finger and rotating in fixed relation to said drive shaft, said finger taking up the thread by rotation from an initial thread contacting position toward take-up position, a stripping surface on said finger in contact with the thread as the finger moves immediately from its take-up position, said crank rotating said take-up finger faster than said thread is moved immediately from its take-up position by said hook whereby said take-up finger sheds said thread as said take-up finger moves from its take-up position toward initial contact with said thread, and said hook taking up the thread and moving it to position for initial contact by said take-up finger as the take-up finger rotates from said take-up position toward said initial contact with the thread.

15. In a sewing machine, a rotary take-up finger having a surface for contacting the thread, a rotary hook for taking up the thread in cooperative relation to said take-up finger, means mounting said take-up finger and hook for rotation on parallel axes vertically spaced from one another, means for holding said thread substantially vertically from a point above the circular path of said finger and leading to said hook, said finger taking up the thread by rotation from an initial thread contacting position at substantially the lowermost position in its path of movement toward take-up position, said hook taking up the thread and moving it to position for initial contact by said take-up finger as the take-up finger rotates from said take-up position toward said initial contact with the thread, means for rotating said take-up finger faster than said thread is moved immediately from its take-up position by said hook whereby said take-up finger sheds said thread as said take-up finger moves from its take-up position toward initial contact with said thread, said hook completing swiftly its take-up of the thread after it is shed by said take-up finger so as to realign said thread for contact once again by said take-up finger.

16. In a sewing machine, a rotary take-up finger having a surface for contacting the thread, a rotary hook for taking up the thread

in cooperative relation to said take-up finger, means mounting said take-up finger and hook for rotation on parallel axes vertically spaced from one another, means for holding said thread substantially vertically from a point above the circular path of said detent and leading to said hook, said finger taking up the thread by rotation from an initial thread contacting position at substantially the lowermost position in its path of movement toward take-up position, said take-up finger having a stripping surface in contact with the thread as said finger rotates from take-up position and toward initial contact with said thread, means for rotating said take-up finger faster than said thread is moved immediately from its take-up position by said hook whereby said take-up finger sheds said thread as said take-up finger moves from its take-up position toward initial contact with said thread, said hook completing swiftly its take-up of the thread after it is shed by said take-up finger so as to realign said thread for contact once again by said take-up finger.

17. In a sewing machine, a take-up finger, means mounting said finger for rotation about a fixed axis, said finger having a surface generated by a line moving in planes parallel to its axis of rotation for contacting the thread at an initial point in the path of rotation of said finger, said surface extending into a detent portion serving as a retainer through its positioning relatively to the thread when said finger first contacts the thread, said detent portion moving with relation to the thread as said finger takes up the thread so as to present a stripping surface to the thread as said finger rotates from take-up position toward its point of initial contact with the thread.

18. In a sewing machine, a take-up finger, means mounting said finger for rotation about a fixed axis, said finger having a surface generated by a line moving in planes parallel to its axis of rotation for contacting the thread at an initial point in the path of rotation of said finger, said surface extending into a detent portion serving as a retainer through its positioning relatively to the thread when said finger first contacts the thread, said detent portion moving with relation to the thread as said finger takes up the thread so as to present a stripping surface to the thread as said finger rotates beyond take-up position toward its point of initial contact with the thread, and means for rotating said take-up finger faster than said thread is moved from its take-up position whereby said take-up finger establishes slack between it and said thread as said take-up finger moves beyond its take-up position.

19. In a sewing machine, a take-up finger, means mounting said finger for rotation about a fixed axis, a drive shaft rotatable in an axis parallel but offset relatively to the axis of rotation of said finger, a crank connection between said drive shaft and the take-up finger whereby said take-up finger rotates at a varying speed relatively to the speed of said drive shaft, said finger having a surface generated by a line moving in planes parallel to its axis of rotation for contacting the thread at an initial point in the path of rotation of said finger, said surface extending into a detent portion serving as a retainer through its positioning relatively to the thread when said finger first contacts the thread, said detent portion moving with relation to the thread as said finger takes up the thread so as to present a stripping surface to the thread as said

finger rotates beyond take-up position toward its point of initial contact with the thread.

20. In a sewing machine, a rotary take-up finger having a surface for contacting the thread, a rotary hook for taking up the thread in cooperative relation to said take-up finger, means mounting said take-up finger and hook for rotation on parallel axes vertically spaced from one another, said finger having a surface generated by a line moving in planes parallel to its axis of rotation for contacting the thread at an initial point in the path of rotation of said finger, said surface extending into a detent portion serving as a retainer through its positioning relatively to the thread when said finger first contacts the thread, said detent portion moving with relation to the thread as said finger takes up the thread so as to present a stripping surface to the thread as said finger rotates beyond take-up position toward its point of initial contact with the thread, and means for rotating said take-up finger faster than said thread is moved immediately from its take-up position by said hook whereby said take-up finger sheds said thread as said take-up finger moves from its take-up position toward initial contact with said thread.

21. In a sewing machine, a rotary take-up finger having a surface for contacting the thread, a rotary hook for taking up the thread in cooperative relation to said take-up finger, means mounting said take-up finger and hook for rotation on parallel axes vertically spaced from one another, means for holding said thread substantially vertically from a point above the circular path of said detent and leading to said hook, said finger having a surface generated by a line moving in planes parallel to its axis of rotation for contacting the thread at an initial point in the path of rotation of said finger, said surface extending into a detent portion serving as a retainer through its positioning relatively to the thread when said finger first contacts the thread, said portion moving with relation to the thread as said finger takes up the thread so as to present a stripping surface to the thread as said finger rotates from take-up position toward its point of initial contact with the thread, means for rotating said take-up finger faster than said thread is moved immediately from its take-up position by said hook whereby said take-up finger sheds said thread as said take-up finger moves from its take-up position toward initial contact with said thread, and said hook completing swiftly its take-up of the thread after it is shed by said take-up finger so as to realign said thread for contact once again by said take-up finger.

22. In a sewing machine of the class described, a take-up mechanism comprising a rotating take-up finger, means guiding a thread so that it extends across the rotary path of said take-up finger to be taken up by said finger, a stripping surface formed as a part of said take-up finger for contacting the thread upon rotation of said finger from its first contact with said thread to take-up position, and means for rotating said finger at such speed relatively to the thread immediately beyond take-up position whereby to relieve the pressure of the thread against said finger.

23. In a sewing machine of the class described, a rotary take-up finger, a rotary bobbin hook, means mounting said finger for rotation about a fixed axis parallel to the axis of said bobbin hook, means for guiding a thread so that it lies

substantially diametrically of the circular path of said take-up finger when it is substantially fully accepted by said bobbin hook and said take-up finger is about to contact said thread to begin the take-up stroke, said finger having an initial thread contacting surface and a stripping surface to contact the thread as said finger rotates beyond take-up position, and means for rotating said finger at such speed relatively to the thread immediately beyond said take-up position whereby to relieve the pressure of the thread against said finger to facilitate the movement of the thread off said finger and its acceptance by said bobbin hook.

24. In a sewing machine of the class described, a rotary take-up finger, a rotary bobbin hook, means mounting said finger for rotation about a fixed axis parallel to the axis of said bobbin hook, means for guiding a thread so that it lies substantially diametrically of the circular path of said take-up finger when it is substantially fully accepted by said bobbin hook and said take-up finger is about to contact said thread to begin the take-up stroke, said finger having an initial thread contacting surface and a stripping surface to contact the thread as said finger rotates beyond take-up position, a drive shaft, means for rotating said bobbin hook in fixed speed relation to said drive shaft, and crank means between said rotary take-up finger and drive shaft for rotating said finger at such speed relatively to the thread immediately beyond said take-up position whereby to relieve the pressure of the thread against said finger to facilitate the movement of the thread off said finger and its acceptance by said bobbin hook.

25. In a sewing machine of the class described, a rotary take-up finger, a rotary bobbin hook, means mounting said finger and hook for rotation on parallel horizontal axes vertically spaced with said take-up finger above said bobbin hook, a needle bar carrying a needle at its lower end, means mounting said needle bar for vertical reciprocation, a tension member positioned vertically above said take-up finger, thread guiding means for guiding said thread so that when it is substantially fully accepted by said bobbin hook and about to be contacted by said take-up finger it will extend from said tension member substantially diametrically and vertically across the circular path of said take-up finger and toward the needle in substantially a single vertical plane, said finger having an initial thread contacting surface to take-up said thread upon rotation of said finger and a stripping surface to contact the thread as said finger rotates beyond take-up position, and means for rotating said finger at such speed relatively to the thread immediately after completion of the take-up whereby to relieve the pressure of the thread against said finger to facilitate the movement of the thread off said finger and its acceptance by said bobbin hook.

26. In a sewing machine of the class described, a rotary take-up finger, a rotary bobbin hook, means mounting said finger and hook for rotation on parallel horizontal axes vertically spaced with said take-up finger above said bobbin hook, a needle bar carrying a needle at its lower end, means mounting said needle bar for vertical reciprocation, a tension member positioned vertically above said take-up finger, thread guiding means for guiding said thread so that when it is substantially fully accepted by said bobbin hook and about to be contacted by said take-up finger it will extend from said tension member sub-

stantially diametrically and vertically across the circular path of said take-up finger and toward the needle in substantially a single vertical plane, said finger having an initial thread contacting surface to take-up said thread upon rotation of said finger and a stripping surface to contact the thread as said finger rotates beyond take-up position, a drive shaft, means for rotating said bobbin hook in fixed speed relation to said drive shaft, and crank means between said rotary take-up finger and drive shaft for rotating said finger at such speed relatively to the thread immediately after completion of the take-up whereby to relieve the pressure of the thread against said finger to facilitate the movement of the thread off said finger and its acceptance by said bobbin hook.

27. In a sewing machine of the class described, a take-up finger, means for rotating said take-up finger, means guiding a thread so that it extends across the rotary path of said take-up finger to be taken up thereby, said take-up finger having a first surface that first contacts the thread to move it in a take-up direction, said take-up finger having a second surface for contacting the thread after rotation of said take-up finger to take up said thread, and said second surface being shaped to allow endwise movement of said thread off the end of said finger.

28. In a sewing machine of the class described, a rotary bobbin hook, a rotary take-up finger, means for rotating said take-up finger on an axis parallel to the axis of rotation of said bobbin hook, means for guiding a thread so that it lies substantially diametrically of the circular path of said take-up finger when it is substantially fully accepted by said bobbin hook and said take-up finger is about to contact said thread to begin the take-up stroke, said finger having a surface that first contacts the thread moving it in a take-up direction as the detent rotates, the continued rotation of said finger moving a second surface thereof against said thread to facilitate the movement of the thread off said finger and its acceptance by said bobbin hook.

29. In a sewing machine of the class described, a rotary bobbin hook, a rotary take-up finger, means for rotating said take-up finger on an axis parallel to the axis of rotation of said bobbin hook, means for guiding a thread so that it lies substantially diametrically of the circular path of said take-up finger when it is substantially fully accepted by said bobbin hook and said take-up finger is about to contact said thread to begin the take-up stroke, said finger having a surface

55

that first contacts the thread moving it in a take-up direction as the detent rotates, the continued rotation of said finger moving a second surface thereof against said thread to facilitate the movement of the thread off said finger and its acceptance by said bobbin hook, a drive shaft, means for rotating said bobbin hook in fixed speed relation to said drive shaft, and crank means between said rotary take-up finger and drive shaft for rotating said finger at such speed relatively to the thread immediately beyond said take-up position whereby to relieve the pressure of the thread against said finger to facilitate the movement of the thread off said finger and its acceptance by said bobbin hook.

30. In a sewing machine of the class described, a head, a take-up disk having take-up means thereon, means mounting said disk for rotation on said head, a cover for said head, means pivoting said cover for movement into and out of covering position, thread guiding means on said head, a second thread guiding means on said cover movable into thread guiding position when said cover moves into covering relation to said head whereby thread is then guided between said head and cover, the thread guiding means of said cover and the thread guiding means on said head coacting to form an eye in effect for the passage of the thread.

31. In a sewing machine of the class described, a head, a take-up disk having take-up means thereon, means mounting said disk for rotation on said head, a cover for said head, means pivoting said cover for movement into and out of covering position, thread guiding means on said head extending transversely thereacross, a second thread guiding means on said cover extending from the inside of said cover toward said disk when said cover is in covering relation to said head, the thread being then guided between said head guide and said cover guide coacting to form an eye in effect for the passage of the thread.

GLEN A. HOLLAND.
